UNITED STATES PATENT OFFICE.

ROBERT HALLOWELL RICHARDS, OF BOSTON, MASSACHUSETTS.

JIG.

No. 901,475.

Specification of Letters Patent.

Patented Oct. 20, 1908.

Application filed June 13, 1908. Serial No. 438,398.

To all whom it may concern:

Be it known that I, ROBERT HALLOWELL RICHARDS, a citizen of the United States, residing at Boston, in the county of Suffolk and State of Massachusetts, have invented 5 certain new and useful Improvements in Jigs, of which the following is a specification.

This invention pertains to apparatus for use in concentrating mills or other establishments, to separate, grade or classify particles of mixed or of approximately uniform sizes, and different specific gravities, and though primarily intended for treating minerals, may be used for other substances. The 10 apparatus is designed to carry out such separation or classification by what I term "hindered settling", which term it is deemed proper to explain or define, in order that the nature and scope of the invention may be 15 better understood. The machine belongs to the general class or type of machines known as "jigs" or "jiggers", but differs from the usual types or forms thereof in important particulars hereinafter explained.

20 There are two conditions under which 25 sands or mineral grains of mixed sizes and different specific gravities can and will settle in water, viz.:

First: where the grains are entirely free 30 from one another, each assuming its natural rate and speed of settling, due to its size, weight, and shape. When, for example, mixed grains of quartz and galena are allowed to settle in water under these conditions, 35 it is found that the grains of the lighter quartz, which settle at the same rate with the heavier galena, have a diameter of (approximately) four times that of the latter. This is called classifying under free 40 settling conditions.

Second: If, on the other hand, water be admitted through a small aperture, or series of apertures, to the bottom of a vessel in which a mass of quartz and galena is resting, 45 the rise of the current of water through the mass causes the quartz and galena grains to arrange themselves according to their ability to settle under such conditions, and it is found that the grain of quartz that settles in juxtaposition with the grain of galena has (approximately) six times the diameter of the latter. This method of classification 50 is called classification under hindered settling condition.

55 The apparatus resembles jigs now in gen-

eral use in that the mass of material is lifted or thrown up by water entering beneath it, and with sudden impulses, but differs from the common form of jigs in that there is no reflux, or downward flow of the water, and hence no tendency to compact the mass of matter under treatment, and retard the flow of water, or lessen the speed of treatment. In falling back through the water the particles arrange themselves in strata in substantial accordance with the ratio above stated as to relative sizes and specific gravities.

The accompanying drawings illustrate the most approved form of the apparatus. 70

In said drawings: Figure 1 is a top plan view of the structure, partly in section; Fig. 2, a longitudinal vertical section on the line 2—2 of Fig. 1; Fig. 3, a transverse vertical section on the line 3—3 of Figs. 1 and 2, 75 looking in the direction of the arrows; Fig. 4, a view illustrating the form of gate used to control the outlets for the concentrates; Fig. 5, a view showing the form of the tailings outlet gate. Fig. 6 a view showing a 80 modified form of the lower section of the apparatus.

The apparatus is preferably formed of cast-iron in two main parts A and B, to the upper one, A, of which is bolted a feed hopper section C. This hopper section can, if desired, be cast with the section A, but it is cheaper and more convenient to cast it separately, and afterward bolt or otherwise fasten it to the section A. As all the material handled by the machine is fed through the hopper, it is desirable that it be provided with a renewable bottom plate or lining D, as shown in Fig. 2. 85

The section A is formed with a longitudinal partition *a*, reaching from its top to a point near its bottom line, and dividing the shell or body A into two longitudinal parts *b* and *c*. These sections *b*, *c*, are in turn subdivided by transverse partitions *d*, 90 which rise from the lower line of section A to the top of section *b*, and to slightly different heights within the chambers or sections *c*, as shown in Figs. 2 and 3, the one nearest the hopper C rising to approximately 100 the level of the delivery end of said hopper bottom, and the others being successively 105 slightly lower.

Chamber or compartment *c* is provided with a tailings discharge spout *e*, the sill 110

or floor of which, at the end next to chamber or compartment *c* is slightly lower than the proximate partition *d*, as seen in Fig. 2. This tailings discharge is provided with a gate *f*, fitting snugly within a metallic guide *g* formed of a sheet metal plate having its edges folded over, as seen in Fig. 1, to form guideways for the vertical edges of the gate *f*. This guide *g* is bolted or otherwise secured to the end wall of chamber *c*, a sheet *h* of caoutchouc, or other suitable packing, being interposed between the guide plate and the wall of the chamber to produce a tight joint. Rising from the gate *f* is a rod *i*, by which to raise and lower it, said rod passing through a two-part clamp *j* provided with a clamping screw *k*, by which the rod, and consequently the gate, may be secured at any desired elevation.

The upper section *A* of the apparatus is further formed with a cross-partitioned lateral extension *E*, the partitions *l* of which are in line with the partitions *d* of chambers or compartments *b*, *c*. The vertical wall of chamber *b* separating said chamber from the lateral extension *E*, is provided with openings *m* for the escape of the concentrates from the different compartments of the chamber or section *b*. Each opening *m* is provided with a gate *n*, having a rod *o*, passing through a clamp *p* of the same character as the clamp *j* of the tailings gate, and provided with a like clamping screw.

Upon referring to Fig. 5 it will be seen that the tailings discharge gate *f* consists of a strip of sheet metal, with a rectangular opening through it of a size corresponding substantially to that of the discharge opening from chamber *c*. When the gate is at its lowest adjustment, the opening through the plate registers with the discharge opening of chamber or compartment *c*, but by raising the gate its lower portion is caused to act as a dam, or adjustable overflow, determining the level to which the water and ore shall stand in chamber *c*.

Fig. 4 shows the form of the gates *n* controlling the outlets *m*, through which the concentrates escape. These gates *n* are similar in form to the gate *f* except that the lower wall or edge of the opening through the plate is formed with a depression *q*, midway between its edges, so that a small quantity of water, with its contained solid matters, may flow through the gate below the level of the major portion of the dam formed by the gate, and that in the event of any considerable or sudden increase in the volume of water, or elevation of its level, it will find a free and broader egress across the whole width of the gate opening. This is found advantageous in practice.

Each compartment of the lateral extension or overflow section *E* has an outlet opening through its bottom, preferably tapped to re-

ceive a discharge pipe *r*, as indicated in Figs. 1 and 3.

The lower member *B* of the apparatus may conveniently be cast in one piece with suitable lugs or brackets *s* to rest upon supporting sills or timbers, but I, of course, do not restrict myself to constructing this in one piece, nor to making it of cast metal, though this is preferred. The lower section is of substantially twice the width of that portion of the upper section *A* containing the chambers or compartments *b*, *c*, the extra width projecting from that side opposite the overflow extension *E*, as seen in Figs. 1 and 2. Cross partitions *t*, registering with the partitions *d*, sub-divide the lower section *B*, and a longitudinal partition *u*, in vertical alignment with the outer wall of chamber *c*, extends from the upper edge of section *B* downward to approximately one-quarter of its depth, as seen in Figs. 2 and 3.

The outer side walls of the lower section *B* are preferably vertical from the upper line downward for some distance, and preferably to a level below the lower edge of the longitudinal partition *u*, from which level they incline inward toward each other producing a hopper-shaped bottom. Each hopper bottom is tapped to receive a cock *F* through which may be drawn off the water contained in the chamber, together with any sediment or solid matter that may lodge therein, though, under the present construction, these hopper-shaped chambers may not be called upon to receive or collect mineral matter.

The upper face of the lower casting or section *B* is recessed to receive a diaphragm *G*, of perforate or foraminous material. In practice I prefer to use woven wire screen material, the sizes of wire and of mesh being variable within quite wide limits, according to the dimensions of the particles to be treated. In practice the diaphragm is formed of two sheets of woven wire screen, the upper one commonly of No. 12 wire with 4 meshes to the linear inch, and the lower one of No. 24 wire with 20 meshes to the linear inch, though these figures and proportions may be varied according to the character and condition of the materials treated, the above being usual or average proportions. The coarse screen is placed above the fine screen for the reason that the pressure of the water is upward, and the coarse screen serves as a backing or support for the fine screen, holding it in horizontal plane and preventing its injury. It also serves to receive the weight of the mineral above at such times as the machine may be out of action, but with a charge of mineral in its compartments.

The screen sections may be made separate, each with its own binding or frame, or one common frame may contain the several sections, as preferred. The edges are firmly clamped between the opposing faces of the

upper and lower sections A and B which are drawn together by bolts, as indicated, the meeting faces being either dressed true to make a water-tight joint or packed, as desired.

The lateral and projecting portion of the lower section or casting B is provided with a top or roof, as shown in Figs. 1 and 3, which is provided with openings v, one opening into each section or compartment formed by the cross partitions t. Directly above each of the openings v is placed a cock or valve H, each valve in turn communicating by a branch or lateral w with a main water supply trunk I. One end of this trunk is closed by a suitable cap or head, and the other end connects with a water supply pipe J, which brings water to the trunk I under suitable head, usually thirty feet, though this is variable at will.

The water supply pipe J is advisably provided with a gate valve K by which the water may be entirely cut off, or its flow regulated at will, and is further furnished, close to the trunk I with a valve, which may be of balanced type, adapted to open and close communication with the trunk I with frequency and regularity. This valve may be of the form illustrated in Fig. 1. As there shown the valve comprises an outer shell or casing L, provided with bearings for a shaft M, one end of which projects beyond the casing and is furnished with a belt wheel N; an annular shell or casing O within the main shell and concentric with the shaft M, said inner shell having an opening at the mouth of the trunk or pipe I; and an open-ended rotary cylinder Q having a central hub and a radial web connecting the hub and the cylinder, the cylinder being provided with diametrically opposite openings which successively register with the opening in the annular shell O.

Water entering at both ends of the rotary cylinder, and pressing in all directions equally therein, the valve will be balanced, the relief incident to registration of one of its openings with the trunk I being offset by relief at or by its corresponding but diametrically opposite, opening. By this construction the tendency to bind, which would be produced by pressure in one direction only, is reduced to a negligible point, and the valve may be freely rotated at any desired speed without the expenditure of any large amount of force.

Any common form of valve capable of operating in this relation may be employed, the pressure being so low in a jig that a balanced valve is not essential.

In the practical operation of the apparatus it is necessary that the valve open and close with very considerable frequency, in order to produce short and sharp pulsations of such frequency as demanded by the par-

ticular class and condition of materials at the time of the treatment. The inertia of the water is such that without some quickly acting force it cannot be caused to respond properly to the rapid opening and closing of the valve; hence I provide in close proximity to the rotary valve an air chamber P. The air contained in this chamber forms a cushion which, at each sudden stoppage of the water column, is compressed by the flow of water into its lower portion, and as promptly reacts to start the water forward to insure its prompt flow through the valve on its next opening. This function of the air chamber is something more than a mere cushioning of the water column to avoid water hammering. Without it, it would be impossible to secure a proper delivery of water in sufficiently rapid and regular pulsations, to the trunk I, and, consequently, to the chambers of the jig or separator. With it the result is perfectly attained.

In practice it is found that more and more air, carried in by the water, collects in the air chamber P, and in time the volume becomes unduly great unless provision be made to relieve it. I, therefore, provide the chamber P with a vent cock x, which may be opened from time to time. In the operation of the jig it is found that a certain volume of air gives better results than either a larger or a smaller volume. If the volume become too small the machine may be stopped, the water turned off at the main valve in the main supply pipe, and the vent cock x opened, whereupon air will enter as the water in the receiver falls, the water having ample outlet through the branch pipes connecting the main with the separating chambers, and thence over the tailings gate. The apparatus being thus constructed, the mineral substances are delivered into the feed hopper C, mingled with water in proper quantity to cause a free flow, and the mingled water and minerals are delivered from said hopper into the chamber c, flowing into the several compartments or pockets formed therein. As the partition a does not reach to the perforate or foraminous diaphragm G, the mingled water and minerals entering the compartments of chamber c will, in greater or less degree, flow laterally into the corresponding compartments of chamber b.

As the water is prevented by the tailings discharge gate f from flowing out at a level below its effective edge, it will be seen that the water will rise not only in chamber c, but also to a like level in chamber b, or to such level lower than the level of the gate f, as may be determined by the adjustment of the gate n in each separate compartment or chamber b.

The water standing in the section or chamber b forms a seal the depth of which, con-

trollable in each compartment or pocket by the gate *n* therein, determines the character as to size and specific gravity, of the particles which will be carried off through the 5 openings *m*, and to the concentrate discharge pipes. Hence by adjusting the several gates *n*, the grading of the concentrates may be accurately determined and controlled. The depth of the seal will, in all cases, be such as 10 to permit the concentrates to pass off, but to preclude the quartz from going with the concentrates through the outlets *m*.

Simultaneously with the delivery of the mingled water and minerals through hopper 15 *C* to chamber or section *c*, and consequently to chamber *b*, water is admitted through the supply main to the trunk *I*, and through the openings *v* to the chambers beneath the compartments in the chambers or sections *b*, *c*, 20 such admission being consequent upon the action of the rapidly opening and closing valve above described. By reason of the depending wall or partition *u* the water is caused first to descend, and then to rise in a substantially vertical column beneath the chambers or sections *b*, *c*, producing a succession of short, sharp upward impulses.

Rising through the foraminous or perforate diaphragm *G* upon which the body of 30 mingled minerals and water rests, the water thus forced upward throws up, and keeps in a loose and separated state, the material in the several compartments, chambers, or sections *b*, *c*, with brief intervals during which 35 such particles tend to fall back to the supporting diaphragm or screen. This alternate upward and downward movement of the particles brings about the stratification, separation, and grading of the particles, 40 which results in the concentrates finally reaching the overflow point, and passing out through the outlets *m*, while the tailings work along to the tailings discharge, and are delivered from the machine.

45 This apparatus embodies to some extent features and principles set forth in an application filed in my name August 2nd, 1905, Serial No. 272,349. The present apparatus, however, differs in many respects from that 50 referred to, and is a "jig" as distinguished from a "classifier" as those terms are used in the trade. This distinction consists in the fact, primarily, that a jig is final in its action, whereas the operation of a classifier 55 is preliminary to treatment upon concentrating jigs, tables, or other final washers. The mesh of the screens or perforate diaphragm of this jig is generally smaller than that of the sieves or screens upon which the 60 material is treated preparatory to coming to the jig; hence this jig does not require a bed of shot, or like material.

65 This jig is devoid of any back flow or suction, which in the case of the ordinary jig compacts the bed and clogs the screens,

thus rendering difficult the upward flow of water as well as the downward passage of the fine mineral particles into the lower collecting chamber, essential to the ordinary jig but not to this jig; therefore, the capacity 70 of this jig is very great. Thus, it has been found by actual use, and with only the upward flow through the chamber as here proposed, one pulsator jig such as here described, having four sieves, or perforate diaphragms, each four inches square making a 75 total for the four sieves of sixty-four square inches, will handle the same quantity of material as eight Hartz jigs of two compartments each, or sixteen sieves in all, each 80 sieve having an area of $19\frac{1}{2}$ by $39\frac{1}{2}$ inches. Thus the ratio between sieve or screen areas is approximately as 1 to 192, each machine handling 100 tons of material per twenty-four hours.

85 Owing to the relatively deep bed of material, and deep concentrates seal it is possible to carry in this jig, the discharge of concentrates is practically automatic regardless of the variation in the feed, and I, therefore, 90 insure clean and uniform concentrates, and this result is aided by the peculiar form of gate opening controlling the outflow of the concentrates.

95 While I have shown and described the chambers or compartments *b* and *c* as provided with cross partitions, dividing said chambers into a series of pockets or distinct chambers, I do not mean to restrict myself thereto, but may omit the cross partitions.

100 Owing to the brief period of time that the mineral particles remain in this jig there is very little attrition of such particles, and consequently the production of slimes is reduced to a minimum, a result important to 105 be attained because of the difficulty of removing the concentrates from such slimes.

Having thus described my invention, what I claim is:

110 1. A jig, comprising an upper and a lower section separated by a perforate or foraminous diaphragm, the upper section being provided with a longitudinal upright partition extending nearly, but not quite, to the perforate or foraminous diaphragm, and 115 thereby dividing said upper section into two parallel chambers; a feed hopper delivering into one of said chambers at one end, said chamber being provided with a tailings discharge at the opposite end and the other of 120 said chambers being provided with an outlet opening in its side wall; an adjustable overflow gate controlling the tailings discharge; an adjustable overflow gate for the outlet 125 opening of the second chamber; a water supply pipe communicating with the space beneath the perforate or foraminous diaphragm; a valve controlling said pipe; and means for opening and closing said valve with frequency and regularity, for the pur- 130

pose of producing a series of upward pulsations through the diaphragm and in the upper chambers, substantially as set forth.

2. A jig, comprising an upper section provided with two chambers arranged side by side and separated by a wall which extends nearly but not quite to the bottom of said chambers, the first chamber being provided with a feed hopper at one end and with a tailings discharge at the opposite end, and the outer wall of the second chamber being provided with an outlet; an overflow gate controlling said outlet; a lower section having a water chamber extending beneath the chambers of the upper section; a perforate or foraminous diaphragm separating the upper and lower sections; and means for producing a series of upward water pulsations through the perforate or foraminous diaphragm without reflux.

3. A jig, comprising an upper section provided with two main chambers arranged side by side, and separated by a wall or partition which extends nearly but not quite to the bottom of said chambers, the first of said chambers being provided with a feed hopper at one end and with a tailings discharge at the opposite end, and the second chamber being provided with outlets in its outer wall; transverse partitions dividing said chambers into smaller chambers or compartments, the partitions of the first chamber rising to about the level of the delivery end of the hopper; a vertically adjustable overflow gate for the tailings outlet; overflow gates for the outlets of the outer chamber, one for each compartment; a lower section having a water chamber extending beneath the chambers of the upper section and provided with cross partitions in alinement with those of the upper section; a perforate or foraminous diaphragm separating the chambers of the upper from those of the lower section; and means for producing a series of upward impulses of water through the foraminous or perforate diaphragm without reflux.

4. The herein described jig comprising an upper section provided with a longitudinal partition dividing it into two chambers and with transverse partitions dividing said chambers into compartments, the longitudi-

nal partition extending nearly but not quite to the bottom of the section, the first chamber being provided with a feed hopper at 55 one end and with a tailings discharge at the opposite end; a lateral extension at the outer side of the second chamber, the wall separating the second chamber and said extension being provided with outlet openings; an adjustable overflow gate guarding the tailings discharge; vertically adjustable overflow gates guarding the outlet openings between the second chamber and the lateral extension; a lower section provided with a longitudinal partition and with transverse partitions registering with the partitions of the upper section; a perforate or foraminous diaphragm separating the upper and lower sections; a trunk or pipe having branches 60 communicating with the spaces beneath the cross partitions of the lower sections, one with each; a valve controlling the supply of water to said trunk and adapted to be opened and closed with frequency; and an air chamber 65 communicating with the supply pipe on the inlet or receiving side of the valve.

5. In a jig, a walled chamber having a feed hopper at one end and a tailings discharge at the opposite end; a second walled 80 chamber at the side of the first, communicating therewith at the bottom, and having outlet openings formed in its outer wall; a perforate or foraminous bottom for said chambers; and means for delivering water upward through said bottom in rapid pulsations without reflux.

6. In a jig, the combination of a separating chamber having an outlet or discharge opening in its wall, and a vertically adjustable gate movable upward from the lower boundary of said opening, and having a notch or depression in its upper edge, whereby a moderate flow may occur through the notch and any sudden increase may occur 95 over the full width of the opening without materially raising the outflow level.

In testimony whereof I have signed my name to this specification in the presence of two subscribing witnesses.

ROBERT HOLLOWELL RICHARDS.
